STONE SETTING TOOL

William F. Bayer, Leonia, N. J.

Application December 22, 1948, Serial No. 66,771

3 Claims. (Cl. 81—7)

1

This invention relates to a stone setting tool.

It is an object of the present invention to provide a stone setting tool adapted to be used with a jewelers' press which will set stones without subjecting them to heavy pressure and will not be likely to break any of the stones during the setting operation, as is done with the tools used heretofore.

It is another object of the present invention to provide a tool arrangement for setting stones in jewelry pieces wherein the stone itself will be projected into the setting piece independently of the opening retaining the stone and in such manner to permit the fingers of the setting piece to be extended over the stone without interference from the wall of the recess in the tool normally holding the stone prior to the final pressing operation and wherein the parts of the tool are spring pressed and adapted to give as the tool members are brought together upon the stone and stone setting piece, and wherein one of the tool members has an engaging part connected with its main part so as to have floating or self-aligning action with the setting piece upon the setting operation being effected and wherein a rubber cushion element is provided between the parts to allow for this action.

Other objects of the present invention are to provide a stone setting tool which is of simple construction, inexpensive to manufacture, easy to operate, compact, consumes little space, has minimum parts, easy to be supplied with the stone prior to the setting operation and convenient to use.

For other objects and for a better understanding of the invention, reference may be had to the following detailed description taken in connection with the accompanying drawing, in which

Fig. 1 is a perspective view of the jewelers' press adapted to receive and retain the tool members of the present invention.

Fig. 2 is a collective and sectional view of the tool members and of the portions of the press retaining the members, the view being taken generally on line 2—2 of Fig. 1.

Fig. 3 is a fragmentary and part sectional view showing the tool members in place above and below a setting in a jewelry piece preparatory to being supplied with a stone.

Fig. 4 is a sectional view of the upper member illustrating the manner in which one of its parts may be shifted in order that the member can be aligned properly with the setting piece.

Fig. 5 is a perspective view of the setting piece before the same has been disposed in and secured to a pin or other member.

Fig. 6 is a fragmentary sectional view of a pin with the stone setting piece secured therein and without the stone.

Fig. 7 is a perspective and fragmentary view of

2

the pin with the stone secured in the setting piece by its prongs.

Referring now to the figures, 10 represents a table on which a press 11 is supported. This press has a base plate 12 and an upwardly extending member 13 thereon adapted to carry die 14 constructed according to the present invention. Also projecting upwardly from the base is an arbor 15 through which is adjustable a rod 16 on which punch member 17, forming a part of the present invention, is connected and fixed by a set screw 18, Fig. 2. The slide is connected to a bell crank 19 pivoted on the arbor 15 at 21 and having a long depending arm 22 extending downwardly through the table 13 to a location near the floor and having a foot tread 23 thereon.

The die 14 has a main part 24 with top and bottom openings 25 and 26 therein. Within the bottom opening 26 is a spring 27 for supporting a pin 28 through its enlargement 29 thereon. The spring 27 is held within the opening 26 by a plug 31 screw threaded into the end of the opening 26.

Adjustable in the opening 25 and surrounding the pin 28 is a sleeve 32 having a cup-shaped recess 33 for receiving the stone. The sleeve 32 is supported on a spring 34 which normally maintains the sleeve 32 in an elevated position and against threaded stop pin 35. The spring 27 is stronger than the spring 34 so that the sleeve 32 may be depressed without the pin 28 being depressed. As the sleeve 32 is depressed, the pin 28 will elevate any stone which may have been disposed in the recess 33. Pin 28 will lift a stone 36 out of the recess and make it secure within a cup setting 37, Fig. 3, while permitting prongs 38 thereof to be depressed by the inclined side walls of the cup-shaped recess 33 over the stone to clinch the same in the manner as illustrated at 39 in Fig. 3. The cup setting 37 is usually fixed to a bar or other jewelry piece 41 by upsetting the projected end thereof in the manner as indicated at 42. By lifting the stone 36 and by having a weaker spring 34 for the surrounding sleeve 32, the prongs 38 can be more readily and quickly bent over the stone, the sleeve 32 giving sufficiently to allow the prongs to slide down over the edges of the stone, and over the top face of the same to clinch the stone. With the stone in place, the pin 28 will give to prevent damage.

50 The punch 17 comprises a main part 44 which is shouldered, as indicated at 45, against the slide 16 and which extends into an opening 46 within the slide for retention by the set screw 18. A lower part 47 is connected to the upper part 44 by a screw 48 threaded at its lower end to receive the part 47 and having an enlarged head 49 resting upon a shoulder 51 in an upper opening 52 of the part 44. Screw 48 extends through an opening 53 which is of larger diameter than that 55 of the screw 48 whereby to allow for lateral shift-

60 of the screw 48.

ing movement of the screw relative to the upper part 44 and the lower part 41 to float and be aligned with the flange 42 of the stone cup setting 37. A rubber cushion 54 is disposed between the parts to allow the lower part 41 to give sufficiently during the setting operation and to prevent damage. The lower part 41 can shift in the manner as illustrated in Fig. 4 in order that its pin 55 can be aligned with the opening in the cup setting 37. The pin 55 is held in its projected position by a spring 56 lying within the part 41 and reacting against the lower end of the screw 48.

To assemble the stone upon the cup setting, the stone is placed in the recess 33 and the jewelry piece 41 with the stone setting 37 held above the same with the prongs 38 lowered into the recess. The punch 11 is then brought down by foot action upon the treadle 23 of the depending arm 22 so that the pin 55 enters the cup setting so that the prongs 38 of the stone setting 37 forced down to a solid stop. Automatically, stone 36 is lifted by pin 28 to hold the stone against the cup setting, while at the same time, making room for the prongs to surround and be clinched upon the stone 36. Upon release of the foot treadle 23, the parts will be automatically brought back to their original position. The stone is gently but firmly fixed in the setting.

While various changes may be made in the detail construction, it shall be understood that such changes shall be within the spirit and scope of the present invention as defined by the appended claims.

What is claimed is:

1. A stone setting tool arrangement comprising a stone receiving die, said die having a main part with openings in the opposite ends thereof, a sleeve adjustable in the top opening, a stop for limiting the outward movement of the sleeve, a spring for urging the sleeve against the stop, said sleeve having a cup-shaped recess for receiving a stone, a pin extending through the main part and through the sleeve for the purpose of projecting the stone into the stone setting on the jewelry piece, a spring in the bottom opening urging the pin upwardly to project the stone into the stone setting while the sleeve is permitted to be retracted, and a punch member adapted to engage the stone setting from the side thereof reversed from that in which the stone is to be set, said pin serving to elevate the stone into the stone setting and leave room for the prongs of the stone setting to be guided about the sides of the stone when the punch and die are brought together upon the stone setting and upon the stone.

2. A stone setting tool arrangement comprising a stone receiving die, said die having a main part with openings in the opposite ends thereof, a sleeve adjustable in the top opening, a stop for limiting the outward movement of the sleeve, a

spring for urging the sleeve against the stop, said sleeve having a cup-shaped recess for receiving a stone, a pin extending through the main part and through the sleeve for the purpose of projecting the stone into the stone setting on the jewelry piece, a spring in the bottom opening urging the pin upwardly to project the stone into the stone setting while the sleeve is permitted to be retracted, and a punch member adapted to engage the stone setting from the side thereof reversed from that in which the stone is to be set, said pin serving to elevate the stone into the stone setting and leave room for the prongs of the stone setting to be guided about the sides of the stone when the punch and die are brought together upon the stone setting and upon the stone, and the spring for maintaining the pin of the die part in an elevated position being stronger than the spring for maintaining the sleeve in its elevated position and against its stop.

3. A stone setting tool arrangement comprising a stone receiving die, said die having a main part with openings in the opposite ends thereof, a sleeve adjustable in the top opening, a stop for limiting the outward movement of the sleeve, a spring for urging the sleeve against the stop, said sleeve having a cup-shaped recess for receiving a stone, a pin extending through the main part and through the sleeve for the purpose of projecting the stone into the stone setting on the jewelry piece, a spring in the bottom opening urging the pin upwardly to project the stone into the stone setting while the sleeve is permitted to be retracted, and a punch member adapted to engage the stone setting from the side thereof reversed from that in which the stone is to be set, said pin serving to elevate the stone into the stone setting and leave room for the prongs of the stone setting to be guided about the sides of the stone when the punch and die are brought together upon the stone setting and upon the stone, and said punch member comprising upper and lower parts, said pin being projected from the lower part, said upper part having an opening therein, a screw extending through the opening of the upper part and threadedly connected to the lower part, the diameter of the opening in the upper part being greater than the diameter of the screw whereby to permit lateral adjustment of the lower part, and a cushion piece disposed between the upper and lower parts.
